UNITED STATES PATENT OFFICE.

JAMES MAY, OF RICHMOND HILL, NEW YORK.

TORPEDO-CATCHER.

1,322,594.

Specification of Letters Patent. Patented Nov. 25, 1919.

Application filed February 18, 1919. Serial No. 277,851.

To all whom it may concern:

Be it known that I, JAMES MAY, a citizen of the United States, residing at Richmond Hill, in the county of Queens and State of New York, have invented certain new and useful Improvements in Torpedo-Catchers, of which the following is a specification.

This invention relates to torpedo guards, and more especially to those of that type known as nets; and the object of the same is to produce a floating torpedo catcher which may be discharged from a gun on the ship attacked, from a howitzer on shore or at some other point, or might be dropped from overhead.

The primary feature of the above invention consists in providing a bag-like net carried horizontally beneath a float with its open mouth directed toward the line along which the torpedo is approaching, so that the latter will run into and be trapped within the net to retard and finally to check its progress until its propelling force is spent.

Another feature consists in providing the float with specially constructed retarding weights which must be dragged through the water by the progress of the torpedo, whereby said progress is retarded vigorously and the torpedo cannot reach its mark.

Yet other objects will appear in the following specification and claims, and reference is directed to the accompanying drawings, in which:—

Figure 1 is a side elevation of this tire catcher, showing a torpedo in dotted lines therein,

Fig. 2 is what might be called a front elevation thereof, and

Fig. 3 is a plan view,

Figs. 4 and 5 are a vertical section and plan view respectively of one of the dragging weights.

The body 1 of this device is buoyant, despite which it may be provided with pontoons 2 alongside it as shown. Superposed upon what might be called the front end of the body is a hood 3 carrying a plug 4 overlying and spaced above the remaining portion of said body, which plug is to be passed into the mouth of a gun, a howitzer, or other machine by which the entire catcher is to be fired.

Rigidly supported by the body at about the center of its length is a ring 10 of some amplitude, the support in this case being

shown as brackets. Forward of this ring there may be another numbered 12, and rearward of it still another numbered 13, and longitudinal straps 14 connect the several rings to hold them in alinement. Additional brackets 15 may be employed to support the front ring. The latter carries tubular guides 16 through which ropes 17 lead downward from a windlass 18 mounted within the hood and having on its shaft a ratchet-wheel 19 engaged by a pawl 20. This ratchet is pivoted at 21 and its tail 22 stands above a head 23 at the upper end of a plunger 24 slidably mounted through the base or body 1; and the lower end of this plunger carries a cupped plate 25 which, when the entire structure strikes the surface of the water, will obviously be pushed upward so that the head of the plunger will strike the tail of the pawl and trip the latter, thus releasing the ropes 17. The lower ends of these ropes carry weights best seen in Figs. 4 and 5. Each has a cupped head 26 and a stem 27 pierced with an eye to which the lower end of the rope 17 is fastened as seen in Fig. 2, in other words the entire head is of mushroom shape. When the windlass is wound up as seen in Fig. 1, these weights are drawn upward against the forward ring 12 and the lower ends of the guides 16. When the device strikes the water and the ratchet is released from engagement by the pawl these weights descend and their ropes run through the guides and off the windlass, or in other words are automatically paid out for a purpose yet to appear.

Carried by and beneath the rear portion of the body or base of this structure is what might be called a bag-shaped net. It is made up of a plurality of rings 30 which, toward the front end of the bag, are substantially of the same size as the fixed rings 10, 12, and 13, but which toward the rear end of the bag decrease in size as seen at the left of Fig. 1. These rings are connected by chains 31 extending longitudinally of the bag along spaced lines, the connection being such that when the bag is distended the rings are separated as shown in this view. Certain rings toward the front end of the bag-like net have eyes 32 in the shape of comparatively large rings which slide on a guide rod 33 carried beneath the body 1. The front ring 30 is connected with the

fixed ring 10 by loops 34. The entire arrangement is such that the bag-like net may be collapsed into comparatively small space when the catcher is to be stored or transported. When a torpedo (see dotted lines T in Fig. 1) enters this bag it opens out the same in a manner which will be clear and the decrease in the size of the rings 30 toward the bottom of the bag causes the 10 same to fit closely over the forward portion of the torpedo so as to trap it, as it were, while the smallest ring at the extreme bottom of the bag is of a size to permit the cap at the point of the torpedo to pass through 15 but to prevent the body of any torpedo from passing.

Assuming now that a ship likely to be torpedoed is provided with a number of these devices. When she is threatened by a 20 submarine the plug 4 is loaded into the mouth of a gun or howitzer on the ship and the same aimed at the submarine. When the latter discharges the torpedo, or even before, one of these catchers is fired onto the 25 water along the line which the torpedo is approaching or must approach; and it is quite possible to fire several of them. Each in striking releases its weights 26 as above described, and each floats with its rigid 30 ring 12 open toward the approaching torpedo T. Now when the latter runs into one of these catchers, the bag-like net is distended as seen in Fig. 1 and the progress of the torpedo will be checked before it can 35 reach the threatened ship. The mushroom-shaped weight will of course drag as seen in dotted lines at the right of Fig. 1 under the force of the torpedo whose travel is therefore gradually retarded, and eventually its 40 progress will be checked. Such would also be the case if this device were fired from a gun or howitzer on land, or if it were dropped from an air ship into the water, provided only that the mouth of the net stands 45 open toward the approaching torpedo.

In Fig. 2 I have shown a slight modification, or rather amplification. This consists of hanging loops 40 and 41 from parts of the device, the former from one of the 50 floats or pontoons and the latter from one of the rings as at 12. In fact these loops may be hung within the forward ring if desired. The obvious purpose is to enlarge the area into which the point of an approaching 55 torpedo can pass, so as to check it on its career.

The foregoing description and the drawings have reference to what may be considered the preferred, or approved form of 60 my invention. It is to be understood that I may make such changes in construction and arrangement and combination of parts, materials, dimensions, et cetera, as may prove expedient and fall within the scope of the 65 appended claims.

Having thus fully described my invention, what I claim as new and desire to secure by Letters Patent, is:—

1. The herein described torpedo catcher comprising a float, a rod carried by and beneath the same, and a collapsible bag-like net slidably mounted on said rod. 70

2. The herein described torpedo catcher comprising a float, a rod carried by and beneath the same, and a bag-like net made up 75 of a plurality of rings decreased in size from one end to the other and a series of longitudinal chains connecting the rings, and eyes on said rings slidably mounted on said rod.

3. The herein described torpedo catcher, the same comprising a float, a ring rigidly carried beneath the same and standing in a vertical plane, and a bag-like net whose mouth is connected with said ring. 80

4. The herein described torpedo catcher, the same comprising a float, a ring rigidly carried beneath the same and standing in a vertical plane, a rod carried by the float and standing above said ring, and a collapsible 90 bag-like net slidably mounted on said rod and with its mouth connected with the rigid ring.

5. The herein described torpedo catcher, the same comprising a float, a rigid skeleton 95 structure carried by and depending from said float, a bag-like net made up of a plurality of rings decreasing in size from one end of the series to the other and a set of longitudinal chains connecting the rings, 100 means for supporting said net beneath the float, a rod beneath the float, eyes on certain of said rings slidably mounted on the rod, and links on the front ring connecting it with said skeleton structure. 105

6. In a torpedo catcher, the combination with a float, a bag-like net carried beneath the same, and means for holding the net with its axis horizontal; of a rigid ring carried beneath the float forward of the mouth 110 of said bag, and cup-shaped weights carried by said ring.

7. In a torpedo catcher, the combination with a float, a bag-like net carried beneath the same, and means for holding the net with its axis horizontal; of a rigid ring carried beneath the float forward of the mouth 115 of said bag and having upright guides along its sides, a windlass on the float, ropes wound thereon and leading downward through said 120 guides, cup-like weights carried by the lower ends of said ropes, and means for releasing the windlass when the float strikes the water.

8. In a torpedo catcher, the combination with a float, a bag-like net carried beneath the same, and means for holding the net with its axis horizontal; of a rigid ring carried beneath the float forward of the mouth 125 of said bag and having upright guides along its sides, dragging weights, ropes connected 130

therewith and leading upward through said guides and to the float, and means for paying out said ropes when the float is dropped on the water.

- 5 9. In a torpedo catcher, the combination with a float, a bag-like net carried beneath the same, and means for holding the net with its axis horizontal; of a rigid ring carried beneath the float forward of the mouth
10 of said bag and having upright guides along its sides, dragging weights, ropes connected therewith and leading upward through said guides and to the float, a windlass on the float around which the ropes are wound,
15 pawl-and-ratchet mechanism for holding said windlass against rotation, a plunger slideable through the float and beneath the tail of the pawl, and a plate on the plunger moved upward by impact with the surface
20 of the water, for the purpose set forth.
10. The herein described torpedo catcher comprising a float, a rod carried by and beneath the same, and a net made up of a plurality of rings decreased in size from one
25 end to the other end, a flexible means connecting the rings together, and eyes on said rings slidably mounted on said rod.

11. The herein described torpedo catcher, the same comprising a float, a ring carried
30 beneath the same and standing in a vertical

plane and a net made up of a plurality of rings decreasing in size from one end to the other and yieldable means connecting the last mentioned rings to each other, and to the first mentioned ring.

35 12. The herein described torpedo catcher, the same comprising a float, a ring rigidly carried beneath the same and standing in a vertical plane, a net made up of a plurality of rings decreased in size from one end to the other, and yieldable means connecting said last mentioned rings to each other and to the fixed ring, and means connected to the fixed ring to retard movement thereof in one direction.

40 13. The herein described torpedo catcher, the same comprising a float, a ring rigidly carried beneath the same and standing in a vertical plane, a net made up of a plurality of rings decreased in size from one end to the other and yieldable means connecting said last mentioned rings to each other and to said first mentioned ring, and cup shaped
45 weights connected to the fixed ring to retard movement thereof in one direction.

50 In testimony whereof I affix my signature in presence of a witness.

55 JAMES MAY.
